UNITED STATES PATENT OFFICE.

LOUIS C. THERRIEN, OF MONTREAL, QUEBEC, CANADA, ASSIGNOR, BY DIRECT AND MESNE ASSIGNMENTS, OF SEVENTEEN TWENTY-FOURTHS TO AUGUSTIN LAVALLÉE AND ADOLPHE OUIMET, OF SAME PLACE, AND TREFFLE GARCEAU, OF BOSTON, MASSACHUSETTS.

STRINGING PIANOS.

SPECIFICATION forming part of Letters Patent No. 288,279, dated November 13, 1883.

Application filed May 18, 1883. (No model.)

To all whom it may concern:

Be it known that I, LOUIS C. THERRIEN, of Montreal, in the Province of Quebec and the Dominion of Canada, have invented a new and useful Device for Stringing Pianos, of which the following is a specification.

My invention relates to improvements in devices for stringing pianos, in which levers are employed for maintaining the desired strain.

10 Heretofore in stringing pianos by means of levers the long arm of the lever has been secured by means of a spring. In such arrangement it is evident that the tension of the spring, and consequently the strain on the string, must 15 vary, since the slight movement of the short arm of the lever, caused by the expansion and contraction of the string, causes a great movement of the long arm, thereby bringing a greater or less strain on the spring.

20 The object of my invention is to provide a device for keeping the strings of a piano-forte under a constant and unvarying tension, so that when a string is once adjusted to the proper tension—say to produce a certain musical 25 note—it will continue to give that note and no other without further adjustment or “tuning,” (as it is commonly called,) regardless of the use, abuse, or changes of temperature to which it may be subjected.

30 My invention is obviously applicable to any line or cord subjected to strain.

My invention consists, mainly, in the combination, with a string secured at one end, of a weight connected to the string by a system of 35 levers proportioned to cause the weight to produce the desired tension, as hereinafter fully set forth.

40 In the accompanying drawings, which illustrate so much of a piano string-frame and sounding-board as is deemed necessary to show my improved device for straining the strings as arranged in the best way now known to me, Figure 1 is a longitudinal section, showing a string of an upright piano with the straining 45 device attached. Fig. 2 is a front view, and Fig. 3 is a rear view of a portion of the string-frame.

The strings A are secured at one end in any

suitable way. In this instance I have shown them attached to wrest-pins, which are preferably used, as by means of them the strings may be brought nearly to tune, and thereby reduce any subsequent adjustment of the levers to the minimum. The strings A are secured at their other ends to the short arms of levers B, having their fulcrums at b, and their long arms connected to the long arms of other levers, B', having their fulcrums at b'.

To the long arm of the levers B' are attached weights C, which, by means of the compound leverage above mentioned, give the desired tension to the strings. The weights C are made of flat plates and quite light—say about one pound each—so as not to objectionably increase the weight of the instrument. Each plate C 55 has small screw-threaded rods or wires c secured to its lower end. These rods c pass through perforations in a plate or board, c', and are provided with nuts c² below the board c'. These nuts c², when the strings are properly 60 tuned, are screwed near to the board c', but not touching it, so as to leave sufficient space for the movement of the plate C incident to the contraction and expansion of the strings. By means of these rods c and the nuts c², the plates 65 C are prevented from becoming displaced or unduly moving when a piano is turned on end or otherwise in transportation. As above mentioned, the strings are very nearly tuned by putting on the weights, and if not in perfect 70 tune they can be made so by means of the screws b² in the ends of the levers B', adapted to turn but prevented from moving endwise, and bearing on the knife-edges of the fulcrums b' of these levers, so that by turning these 75 screws their threads engage with the knife-edges, whereby the position of these levers in relation to their fulcrums can be delicately and accurately adjusted, so as to increase or diminish the strain on the string to the slight 80 extent required.

It is evident that when the strings and weights are once properly adjusted they will remain so indefinitely, and the usual frequent tunings heretofore required in piano-fortes 85 will not now be necessary. I have held pieces

of red-hot iron in proximity to strings tuned in this way, and I have also kinked such strings with a pair of nippers without varying their tones in the slightest.

5 I claim as my invention—

1. In a piano-forte, the combination, with a string, A, of the compound levers B and B' and weight C, arranged substantially as described, and for the purpose set forth.

2. The combination, in a piano-forte, of the 10 string, the compound levers, the weight, the screw, and the fulcrum having its edge adapted to engage with the thread of the screw, substantially as and for the purpose set forth.

LOUIS C. THERRIEN.
